UNITED STATES PATENT OFFICE.

LOUIS BURMEISTER, OF MILWAUKEE, WISCONSIN.

ELEVATOR LEG.

Application filed March 22, 1926. Serial No. 96,397.

This invention relates to improvements in elevator legs and spouting such as are used in grain and flour elevators.

Heretofore elevator legs of the type referred to have comprised longitudinally extending sections fitted together and provided at their adjacent edges with complementary flanges through which fastening bolts passed to hold the sections in assembled relation. The conveying mechanism enclosed by these legs requires repair or overhauling from time to time. It is then necessary to remove the relatively great number of these bolts for the purpose of disassembling the leg sections, this operation requiring considerable time and being very inconvenient. In view of the inconvenience with which the sections are assembled and bolted together, furthermore, the practice has been followed of shipping them already assembled, the cost and trouble of shipping thereby being greater than if the legs were shipped in knocked down condition with the sections arranged in nested relation.

One of the objects of the present invention is to provide improved means for fastening or securing together the sections comprising an elevator leg of the character referred to, such means being readily applied to fasten the leg sections securely together, or readily and quickly removed to permit of disassembly of the sections, and which provides a proper and sufficient seal at the seams or joints to prevent leakage at these points, all this being accomplished without the use of fastening bolts such as have been used in legs of this type constructed heretofore.

Another object is to provide an improved elevator leg of the character referred to wherein the various parts comprising the same may be readily assembled on the job, thus permitting shipping of the legs in knocked down condition with the sections arranged compactly in nested relation.

Other objects and advantages will hereinafter appear.

For the purpose of illustrating the invention, several embodiments thereof are shown in the drawings, in which:

Figure 1 is an elevational view, showing the manner in which the improved elevator leg is placed in an elevator of the character referred to;

Fig. 2 is an enlarged section on the line 55 2-2 of Fig. 1; and

Figs. 3, 4 and 5 are views similar to Fig. 2, showing modified forms.

In Fig. 1 the usual boot 10 and the head 11 of a grain or flour elevator are shown as 60 being arranged, one above the other, on different floors of a building, stubs such as shown at 12 extending through and being supported by the intervening floor or floors 65 and serving to connect the legs of the elevator. The respective lower ends of legs 13 fit over the upper ends of stubs 12, as shown, while the upper ends of these legs are fitted to the head in any suitable manner. The lower ends of legs 14 are fitted to the boot 70 10, while the upper ends of these legs are fitted to the lower ends of stubs 12. The usual endless conveyor (not shown) with buckets attached passes through legs 13 and 14 and over suitable wheels or sheaves journaled in the boot and head, the grain or flour being fed into the boot and elevated by means of the conveyor to the head. As more clearly shown in Fig. 2, the leg 13 comprises a pair of complementary sections 15 80 fitted together to form a leg substantially rectangular in cross section, the adjacent edges of these sections being bent outwardly to form complementary flanges 16. Each of the flanges 16 is pressed outwardly to form 85 longitudinally extending oppositely arranged beads 17. U-shape fastening members 18 are fitted over flanges 16, as shown, and comprise sides or portions 19 provided with outwardly and longitudinally extending beads 20 adapted to nest and interlock with beads 17, and resilient portions 21 connecting sides 19 and urging the latter inwardly and yieldingly holding the same in interlocking engagement with flanges 16, the 90 beads 17 and 20 providing for the locking action and also forming a tight joint preventing leakage, etc.

In constructing or erecting a leg two sections 15 are fitted together, as shown in Fig. 2, and the fastening members 18 placed over flanges 16 and forced in position, as shown, the resilient portions 21 permitting the sides 19 to spread until beads 20 snap into interlocking relation with the flange beads 17, the resilient portions 21 then acting to urge sides 19 inwardly and to yieldingly hold the sides in interlocking engagement with flanges 95 100 105.

16. Should it become necessary to disassemble the leg for the purpose of inspecting and repairing the movable parts of the conveyor, members 18 may be forced out of place, any suitable tool being employed for this purpose, the resilient portions 21 permitting sides 19 to spread so that beads 20 ride over beads 17 and are moved out of interlocking relation therewith.
- 10 From the foregoing it will be seen that the U-shape members 18 provide means for fastening or securing the leg sections securely together and at the same time provide a tight joint, and that these members 15 may be readily removed or placed in fastening position, all this being accomplished without the use of bolts or other fasteners such as used in legs of this type constructed heretofore.
- 20 In Fig. 3 the joints or seams are shown as being in the center of opposite sides of the leg, these joints being of the same construction as the joints shown in Fig. 2 and described above, and which are at diagonally opposite corners or edges of the leg.
- 25 In Fig. 4 is shown another modification, in which the joints or seams are at adjacent corners or edges of the leg.
- In the modification shown in Fig. 5, one 30 of the leg sections 23 is provided with the beaded edge portion 24, a spring clip 25 being formed from the edge of the adjacent section 26 and being shaped for interlocking engagement with the bead of flange 24, as shown, clip 25 being held in such engagement by virtue of its own resiliency.
- The fastening members 18 may be removed by either forcing the same outwardly 35 from flanges 16 or by slipping the same longitudinally out of interlocking relation with the flanges. Members 18 may be applied by either forcing the latter inwardly over these flanges or slipping the same longitudinally over the latter.
- 40 While the improvements have been especially described and referred to herein as in connection with the construction of elevator legs, it will of course be appreciated that the invention is not limited in this 45 particular. On the other hand, it is equally applicable to the construction of spouting 50 such as is used very widely in grain elevators, mills, etc. for conveying the grain, flour, etc. to various locations after it has

been elevated. It is desired, therefore, that the foregoing specification and the appended claims be construed in a broad enough sense to include these and analogous uses.

While several embodiments of the invention have been shown and described, it will be understood, of course, that various changes may be made without departing from the spirit of the invention or the scope of the claims.

The invention claimed is:

1. In an elevator, a conduit made up of complementary sections having abutting portions engaging in face to face relation without interlocking, one of said abutting portions having an outwardly directed projection and a spring clip cooperable with said abutting portions and having a seat receiving the outwardly directed projection of the abutting portion for releasably securing the sections in assembly. 65
2. In an elevator, a conduit made up of complementary sections having abutting flanges engaging each other in face to face relation, the flanges having outwardly directed projections, the projection of one flange being spaced from the projection of the other, and a resilient U-shaped clip embracing the flanges and snugly engaging the same, the clip having seats in which the projections are snugly fitted whereby the clip is held in engagement with the flanges and the flanges are releasably interlocked to maintain the sections in assembly. 70
3. An elevator leg made up of complementary longitudinally extending sections, the sections having longitudinally extending flanges abutting each other in face to face relation in assembly, the flanges having outwardly directed longitudinal beads, the bead of one flange being spaced from the bead of the other flange in the assembly, and resilient U-shaped clips embracing the abutting flanges, each clip having a resilient body portion and a pair of legs extending from the body portion, the legs having beads releasably interlocking with the outwardly directed beads of the abutting flanges in the assembly whereby the sections are releasably maintained in assembly. 75
4. In witness whereof, I hereto affix my signature. 80

LOUIS BURMEISTER.
